UNITED STATES PATENT OFFICE

2,664,315

BRUSH ASSEMBLING MACHINE

John G. Baumgartner, Oswego, Ill.

Application January 19, 1950, Serial No. 139,361

13. Claims. (Cl. 300—2)

1.

This invention relates generally to assembling machines, and more particularly to a machine for assembling the stem of a brush having bristles thereon to a cap which serves as the handle for the brush.

It is now common practice to secure brushes which are used for applying lacquer or similar material to a cap which acts both as the closure for a bottle or other container in which the material is provided, and also as a handle for holding the brush. In particular such an arrangement is commonly used with fingernail polish with the cap which closes the bottle containing the polish also supporting the stem of the brush and serving as a handle for the brush so that the brush is always readily available and can be held without danger of contacting the fingernail polish.

In order to save space in the handling, shipping and storing of such brushes it is preferable to pack the stem and bristle portions of the brushes, and the cap portions, in separate containers. It is obvious that this results in a great saving in space as compared with that which would be required to pack the assembled units. It is therefore proposed to handle the portions of the brush separately and then assemble them just before the brush is applied to the bottle with which it is to be used. To practice this procedure, it is necessary that a simple device be provided for rapidly assembling the stem and cap to provide the completed unit. Such a machine should be capable of operation by an unskilled operator and should not require specialized maintenance as mechanics skilled in such machines might not be available at the plant in which the brushes are finally applied to the bottles or other containers.

It is therefore an object of the present invention to provide a simple automatic machine for assembling the stem and bristle portion of a brush with a cap portion which is thereafter used as the handle for the brush.

It is another object of this invention to provide a machine for rapidly assembling the stem and handle portions of a brush which can be operated by an unskilled operator and which provides a secure connection between the parts, without requiring close tolerances in the parts, and without damaging the parts so that a substantial number must be rejected.

A feature of this invention is the provision of a machine for assembling the stem and bristle portion of a brush with the handle portion thereof, in which the two portions are individually fed to an assembly point with the handle portion being held in a fixture and the stem

2.

inserted therein to provide a secure connection therewith.

A further feature of this invention is the provision of an automatic assembling machine for brushes having cam means on a single shaft for controlling all moving parts required in the assembling operation.

A still further feature of this invention is the provision of a machine for assembling stem and bristles portions of brushes in caps which serve as handles, in which the stem and bristle portions are fed along a channel and then individually positioned between clamping jaws which engage the stem and then slide as a unit to force the end of the stem into a recess in the cap. After the stem and cap are united the cap is removed from the fixture and the assembled brush is dropped from the machine.

Further objects and features will be apparent from a consideration of the following description taken in connection with the accompanying drawings in which:

Fig. 1 is a perspective view showing the assembling machine;

Fig. 2 is a cross sectional view through the machine showing the cam means and the linkages connected therewith;

Fig. 3 is a cross sectional view showing the assembly slide in a position with the stem of the brush inserted in the cap;

Fig. 4 is a cross sectional view along the lines 4—4 of Fig. 3 illustrating the ejecting and clamping structure;

Fig. 5 is a perspective view illustrating the dropping fingers of the ejecting mechanism;

Fig. 6 illustrates the assembly slide;

Fig. 7 is an exploded view showing the various components of the assembly slide;

Fig. 8 is a cross sectional view along the lines 8—8 of Fig. 3 illustrating the fixture in which the caps are held during assembly;

Fig. 9 shows the container for the caps and the agitating means therefor;

Fig. 10 is a cross sectional view along the lines 10—10 of Fig. 9;

Fig. 11 is a detail view of the openings in the container;

Fig. 12 illustrates a completed brush and,

Fig. 13 illustrates a modified structure for feeding stem and bristle portions of brushes.

In practicing the invention there is provided a machine for assembling stem and bristle portions of brushes with caps which serve as handles for the brushes. The machine includes a frame or table on which the operating parts of the ma-

chine are supported. Positioned substantially centrally on the table is an assembly fixture which is shaped to receive a cap and hold the same in a position so that a stem can be inserted in a recess provided therein. A slide is provided including a retractable clamping jaw for holding the stem and bristle portion of a brush, and sliding as a unit into a position in which the stem is forced into the recess in the cap. A container is provided for the caps and a conveyor interconnects the container and the fixture for supplying the caps thereto. The container has openings through which caps are supplied in a particular position to the conveyor, with a rotating vane agitating the caps so that they move through the openings. Feeding means are provided for the stem and bristle portions including a channel in which a single layer of such portions may be positioned and a finger for urging the portions toward the assembly point. Ejector means are provided for removing the stem and bristle portions individually from the feeding channel and positioning them in the clamping jaws. For causing automatic operation of the machine, cam means are provided which are interconnected through mechanical linkages with the ejector means, the clamping means and the assembly slide so that the stem and bristle portion is held in the clamping jaws and the end thereof is forced into the recess of the cap.

Referring now to the drawings, the table is shown including a top 20 and a front supporting frame 21 and a rear supporting frame 22, with a brace 23 interconnecting the frames to provide a rigid structure. A bracket 24 is secured to the table at the back for supporting the container 25 for the caps. The container 25 is connected through a conveyor 41 to a fixture 42 supported on the top 20 (Fig. 3), which holds a cap 19 while the stem and bristle portion is being assembled thereto. A complete assembled unit is shown in Fig. 12 with the stem 18 having bristles 17 secured thereto. For supporting the feeding mechanism for the stem and bristle portions of the brushes, a shelf 26 is provided on one side. A channel 27 is provided in the shelf through which the stem and bristle portions are fed to an ejector mechanism 28 positioned above the assembly slide 29. The assembly slide is supported on the table 20 by track members 30 having slanting edges engaging corresponding slanting edges on the slide. For causing automatic operation of the machine, a motor 31 is provided which operates through pulleys 32 and 33 to drive shaft 34 on which cams 35, 36 and 37 are mounted. The cam 35 operates through arms 38 and 39 to operate the ejector mechanism 28, the cam 37 operates through arms 39 and 40 to operate the assembly slide 29, and the cam 36 operates through a linkage to control the operation of the clamping means on the slide as will be further described.

The mechanism for feeding the stem and bristle portions of the brushes to the assembly slide is best shown in Figs. 1 and 2. As previously stated, the shelf 26 has a channel 27 therein formed by rails 44 having inturned lips 45 which hold the portions in a single layer. A finger 46 secured to arm 47, which is pivotally and slidably supported on the rod 48, acts as a follower to push the stem and brush portions toward the assembly slide. The tubular support 49 for the arm 47 is pulled toward the assembly slide by cord 50 to which is attached weight 51.

The ejector mechanism for individually positioning the stem and bristle portions of the

brushes on the assembly slide is shown in Figs. 2, 3, 4 and 5. As best shown in Fig. 4, pivotally mounted fingers 55 are provided having notches 56 for retaining the stem and bristle portions at the end of the channel 27. The fingers are secured to shaft 57 which is spring biased through arm 58 and spring 59 to the position shown in Fig. 4. For ejecting each portion individually, a vertical slide 60 is provided which slides in a channel formed by the supporting member 61 and the plates 62. As shown best in Fig. 2, the slide 60 is connected to arm 38 which is coupled through arm 37 to the cam 35. The spring 63 tends to pull the slide down with the cam 35 normally holding the slide in the upward position. When the cam 35 is in such position that the recess 65 therein is engaged by the roller 64 at the end of the arm 37 the spring 63, operating through the linkage, will cause the slide 62 to move downwardly. The bottom end of the slide will engage the stem and bristle portion held in fingers 55 and cause the fingers to rotate to a position so that the stem and bristle portion can drop to the slide 29 in the position shown in dotted lines and indicated at 66. To receive the stem and bristle portion, the movable clamp jaw 67 must be withdrawn from the fixed jaw 68 to a position as indicated at 67a so that the stem can drop between the fixed clamp jaw 68 and the movable clamp jaw 67. The slide 60 has a projecting finger 69 which holds the end of the stem so that it will not move longitudinally as it is dropped into the clamping jaws in the assembly slide.

As previously stated, the assembly slide 29 is supported on the table 20 for sliding movement between the tracks 30. The slide is moved by arm 40 which is pivotally connected to arm 39. The arm 39 is pivotally supported by the sleeve 70 supported by brackets 71 and 72 which are secured to the top 20. The bracket 71 also cooperates with bracket 73 to support the shaft 34 on which the cams are mounted. The arm 39 is biased toward the back of the table by spring 74 and is moved against the force of the spring 74 by roller 75 which bears against the cam 37. The cam 37 has a low spot which, in the position shown in Figs. 1 and 2, is at the top, and when the cam rotates so that the low spot engages the roller 75 the slide 29 will be moved by action of the spring 74 toward the back of the table.

The construction of the slide and the clamping means thereon is best shown in Figs. 3, 4, 6 and 7. The slide has a recess 80 in the bottom surface and a slot 81 extending from the top surface thereof through to the recess. The fixed clamping jaw 68 may be bolted or otherwise secured to the slide 29. The movable clamp jaw 67 is held in the recess 80 by the block 82 which may be bolted to the slide 29. The movable jaw 67 has a recess 85 therein which cooperates with the raised portion 86 on the block 82 so that the sliding jaw 67 is held between the block 82 and the top surface of the recess 80 and can slide therebetween. In Fig. 4, the jaw is shown in the closed position in solid lines and in two different open positions by the dotted lines 67a and 67b. The movable jaw 67 has an opening 83 therein with a slot extending therefrom which receives a finger 90 secured to the slide 29. The finger 29 prevents the movement of the brush with the movable jaw 67 as will be more apparent from the following description.

The movable jaw 67 is moved by a pin 87 extending in opening 83, which is secured to one

end of arm 88, pivotally secured to the slide 29 intermediate the ends thereof by the pivot 89. The arm 88 has a slot 91 therein at the other end for receiving pin 92 supported on the cross slide 93. As shown best in Fig. 2 the cross slide 93 has a roller 94 thereon which engages the surface of the cam 36. The cross slide 93 is biased to the left (Fig. 2) by spring 95 and is selectively moved to the right by engagement between the roller 94 and the cam 36. This movement is transferred to the movable jaw 67 to close the jaw when the roller 94 engages the low portion 96 on the cam and to open the jaw when the roller engages the high portion 97. An intermediate portion 98 is provided in which the jaw is partly opened. From a consideration of Figs. 2, 4 and 6, it will be apparent that when the roller 94 is riding on the low portion 96 of the cam the jaw will be in the closed position as shown by solid lines in Fig. 4. When the roller 94 is riding on the high portion 97 of the cam the jaw will be in the widest open position as shown by the dotted line 67b. When the roller 94 bears against the intermediate portion 98 of the cam 36 the jaw will be open to receive a stem and bristle portion as shown by the dotted line 67a.

Considering now the container for the caps and the conveyor for supplying the caps to the assembly fixture, reference is made to Figs. 1, 3 and 8 to 11. The container 25 is mounted on base 100 which is supported on the bracket 24. A separate motor 101 drives pulley 102 connected to worm gear 103 which in turn drives gear 104. The gear 104 is connected through shaft 105 to the agitator 106 which includes three vanes. The agitator rotates within the container 25 to move the caps around. Extending around one side of the base is a channel 107 which connects with a downwardly curved channel 108 to form a conveyor for delivering the caps from the container to the fixture. Openings 109 are provided around the sides of the container through which the caps can move into the channel 107. The openings 109 are of such shape that the caps can pass through the opening only in one position as is clearly shown in Fig. 11. This results in the caps being fed into the channel 107 in a particular position. The channels 107 and 108 are of such configuration that the caps cannot change their position therein, and are positioned at such an angle that the caps will be fed by gravity down these channels to the fixture 42 which receives each cap and supports the same as the stem is assembled therewith.

As previously stated, the caps 19 have recesses 110 therein into which the stem 18 of the brush fits very snugly. As shown in Fig. 3, a cap when in the position in the fixture 42 is positioned so that the recess therein is aligned with the stem 18. When the stem is clamped in the jaws of the slide and the slide is moved toward the back of the table, the stem 18 is forced into the recess 110 providing a secure connection between the stem and the cap 19 so that the brush is thereby assembled.

Considering now the operation of the assembling machine, the stem and bristle portions are fed through the channel 27 and the cap portions are fed through the conveyor 41 with one cap being positioned in the fixture 42. The motor 31 drives the shaft in a clockwise direction as shown in Fig. 1. The intermediate portion 98 of the cam 36 engages the roller 41 so that

the movable jaw 67 is part way open (line 67a, Fig. 4). The cam 35 rotates to a position so that the roller 64 drops in the recess 65 and the ejector slide 60 moves down and causes one stem and bristle portion to drop through the slot 81 in the slide to the position between the jaws 67 and 68. The cams continue to rotate with the slide 60 being moved up through connection between the roller 64 and the cam 35. 10 As the cam 36 rotates further, the roller 94 drops down to the lowest point 96 on the cam 36, and the movable jaw 67 then moves to the clamping position. Fig. 2 shows the cams just 15 reaching this position with the roller 94 moving from the intermediate portion 98 to the lowest portion 96 and the cam 35 having just passed the point where the recess 65 allows the roller 64 to move to the right.

The stem and bristle portion is therefore tightly clamped in the jaws of the assembly slide. As the cams continue to rotate the low point on the cam 37 engages the roller 65 which controls the movement of the slide and the slide is moved toward the back of the table. In Figs. 1 and 2 the low point on cam 37 is shown at the top, and rotation through approximately 90 degrees from the position shown will cause movement of the slide. The stem is thereby inserted in the recess in the cap and is securely positioned therein and the brush is therefore assembled. Continued movement of the cam 37 will cause the roller 65 to be moved away from the shaft 34 and the slide to be withdrawn toward the front of the table. This will cause the entire brush including the cap 19 to be moved so that the cap is withdrawn from the assembly fixture and the next cap drops down into the fixture. After the slide 29 is thus withdrawn, the highest part 97 of the cam 36 will engage the roller 94 causing the jaw 67 to move to its farthest open position (indicated at 67b, Fig. 4) so that the assembled brush will drop from the clamping jaws into a container such as the box 112 under the machine. The finger 98 prevents movement of the brush with the movable jaw 67.

In Fig. 13 there is illustrated a brush assembly machine generally similar to that in Fig. 1 except that the channel for feeding the stem and bristle portions of the brushes to the assembling slide is curved. The slide is supported on shelf 115 on which are secured track members 116 which provide a channel for the stem and bristle portions. In order to urge the portions of the brushes toward the assembly slide 29, a finger 117 is provided which is connected to the pivotally mounted post 118. For biasing the finger in a counterclockwise direction, the spring 119 is provided which is wrapped around pulley 120 on the post 118. Such a curved channel is advantageous when the stems of the brushes have enlarged portions at the ends which fit into the caps. Such enlarged portions take more space and accordingly are positioned in the larger outer track.

It is seen from the above that there is provided an improved machine for assembling handles to the stems of brushes, which machine is of relatively simple construction and is fully automatic in operation. The machine handles the parts of the brushes in such manner that the parts are not damaged and accordingly the number of rejects is very small. The machine is very rapid in operation so that a large number of brushes can be assembled by a single machine. The machine, being very easily oper-

ated, can be used in the plant where the brush is applied to the container for the material with which the brush is to be used so that the stem and bristle portions and the cap portions may be separately handled until the brushes are assembled on the containers.

Although certain embodiments of the invention have been described which are illustrative thereof, it is obvious that various changes and modifications can be made therein without departing from the intended scope of the invention as defined in the appended claims.

I claim:

1. A machine for assembling brushes which include first portions having elongated stems made of resilient material and bristles secured thereto and caps which serve as handles for the brushes and which have recesses therein for receiving the stems, said machine including in combination, an assembly slide, an assembly fixture adjacent said assembly slide having such configuration to receive a cap and support the same in a predetermined position, conveying means for individually providing the caps in said assembly fixture in said predetermined position, said assembly slide having clamp means for releasably engaging the sides of the elongated stem of a brush for holding the same in a position in alignment with the recess of the cap held in said assembly fixture, feeding means for receiving a plurality of stem and bristle portions and supplying the same adjacent said assembly slide, ejector means for individually removing said stem and bristle portions from said feeding means and positioning the same in said clamp means, and operating means for moving said slide so that the stem held in said clamp means is forced into the recess in the cap supported in said fixture, said operating means thereafter withdrawing said slide together with the assembled brush for removing the cap thereof from said assembly fixture, and then releasing said clamp means to thereby drop the assembled brush from said fixture.

2. A machine for assembling brushes which include a first portion having an elongated stem made of resilient material and bristles secured thereto and a cap which serves as a handle for the brush and which has a recess therein for receiving the stem, said machine including in combination, an assembly slide having clamp means with first and second jaw portions movable with respect to each other in a first direction for releasably holding the stem of a brush therebetween, ejector means for individually dropping said stem and bristle portions in said clamp means between said jaw portions, an assembly fixture adjacent said assembly slide having such configuration to individually receive the caps and support the same with the recess therein aligned with the stem held in said clamp means, and operating means for moving said slide in a direction substantially at right angles to said first direction so that the stem held in said clamp means is forced into the recess in the cap supported in said fixture.

3. A machine for assembling brushes which include a first portion having an elongated stem made of resilient material and bristles secured thereto and a cap which serves as a handle for the brush and which has a recess therein for receiving the stem, said machine including in combination, an assembly slide having clamp means with movable jaw portions adapted to engage the elongated stem of said first brush

portion, feeding means for receiving a plurality of the stem and bristle portions and supplying the same adjacent said assembly slide, an assembly fixture adjacent said assembly slide for holding a cap in such position that the recess therein is aligned with a stem which is held in said clamp means, conveyor means for individually providing the caps in said assembly fixture, ejector means for individually positioning the stem and bristle portions in said clamp means, and automatic means for controlling operation of said machine including cam means, power means for driving said cam means, and mechanical means connecting said cam means to said slide, said clamp means and said ejector means, said cam means being of such configuration to cause operation of said clamp means to move said jaw portions to an open position to receive a stem and bristle portion therebetween, operation of said ejector means to position a stem and bristle portion in said open clamp means, operation of said clamp means to move said jaw portions to a clamping position to hold the stem therebetween, operation of said slide in a reciprocating action to force the stem into the recess of the cap in said fixture and to withdraw the assembled brush for removing the cap from said fixture, and operation of said clamp means to move said jaw portions to an open position to release the assembled brush therefrom.

4. A machine for assembling brushes which include a first portion having an elongated resilient stem and bristles secured thereto and a cap which serves as a handle for the brush and which has a recess therein for receiving the stem, said machine comprising an assembly slide having clamp means for holding the stem of a brush, feeding means for receiving a plurality of stem and bristle portions and supplying the same adjacent said assembly slide, ejector means for individually positioning the stem and bristle portions in said clamp means, an assembly fixture adjacent said assembly slide for holding a cap in such position that the recess therein is aligned with a stem which is held in said clamp means, conveyor means for individually providing the caps in said assembly fixture, and automatic means for controlling the operation of said machine, including a shaft and means for continuously driving said shaft, first, second and third cams supported on said shaft, a first mechanical linkage connecting said first cam to said ejector means for causing operation thereof to position a stem and bristle portion in said clamp means, a second mechanical linkage connecting said second cam to said clamp means for causing operation thereof to hold the stem therein, and a third mechanical linkage connecting said third cam to said slide for causing operation thereof to force the stem into the recess of the cap in said fixture and to withdraw the assembled brush for removing the cap from said fixture, said second linkage and said second cam causing operation of the clamp means to release the assembled brush, said cams being of such configuration and being so positioned on said shaft that said operations take place in the order stated.

5. A machine for assembling brushes which include a first portion having an elongated resilient stem with bristles secured thereto and a cap which serves as a handle for the brush and which has a recess therein for receiving the stem, said machine comprising an assembly slide having clamp means for holding the stem of

a brush, feeding means for receiving a plurality of stem and bristle portions and supplying the same adjacent said assembly slide, ejector means for individually positioning the stem and bristle portions in said clamp means, an assembly fixture adjacent said assembly slide for holding a cap in such position that the recess therein is aligned with a stem which is held in said clamp means, conveyor means for individually providing the caps in said assembly fixture, and automatic means for controlling the operation of said machine, including a shaft and means for continuously driving said shaft, a plurality of cams supported on said shaft, a first mechanical linkage connecting a first one of said cams to said clamp means, a second mechanical linkage connecting a second one of said cams to said ejector means, and a third mechanical linkage connecting a third one of said cams to said slide.

6. A machine for assembling brushes which include a first portion having an elongated resilient stem and bristles secured thereto and a cap which serves as a handle for the brush and which has a recess therein for receiving the stem, said machine comprising an assembly slide having clamp means for receiving and holding the stem of a brush, feeding means for receiving a plurality of stem and bristle portions and supplying the same adjacent said assembly slide, ejector means for individually positioning the stem and bristle portions in said clamp means, an assembly fixture adjacent said assembly slide for holding a cap in such position that the recess therein is aligned with a stem which is held in said clamp means, conveyor means for individually providing the caps in said assembly fixture, and automatic means for controlling the operation of said machine, including a shaft, means for continuously driving said shaft, first, second and third cams supported on said shaft, a first mechanical linkage connected to said clamp means and cooperating with a first portion of said first cam for causing operation of said clamp means to a position for receiving a stem and bristle portion, a second mechanical linkage connecting said second cam to said ejector means for causing operation thereof to position a stem and bristle portion in said clamp means, said first cam having a second portion which cooperates with said first mechanical linkage for causing operation of said clamp means to hold the stem therein, and a third mechanical linkage connecting said third cam to said slide for causing operation thereof to force the stem into the recess in the cap which is in said first fixture and to withdraw the assembled brush, said first cam having a third portion which cooperates with said first mechanical linkage for causing operation of said clamp means to release the assembled brush.

7. A machine for assembling brushes which include a first portion having an elongated resilient stem and bristles secured thereto and a cap which serves as a handle for the brush and which has a recess therein for receiving the stem, said machine including in combination, an assembly slide, an assembly fixture adjacent said assembly slide for holding the caps individually therein in a predetermined position, said assembly slide having clamp means for receiving and holding the stem of a brush in a position in alignment with the recess in the cap supported in said fixture, ejector means for individually positioning the stem and bristle portions in said clamp means,

and automatic means for controlling the operation of said machine, including a shaft and means for continuously driving said shaft, first, second and third cams supported on said shaft, a first mechanical linkage connecting said first cam to said clamp means, a second mechanical linkage connecting said second cam to said ejector means, and a third mechanical linkage connecting said third cam to said slide.

10. 8. In a machine for assembling brushes which include a first portion having an elongated resilient stem with bristles secured thereto, and a cap which serves as a handle for the brush and which has a recess therein for receiving the stem, the combination including, means for holding a cap in a predetermined position, an assembly slide having a fixed jaw portion and a movable clamping jaw portion supported thereon, means including an arm pivotally connected to said slide for selectively moving said movable clamping jaw portion from a first position spaced from said fixed jaw portion for receiving a stem from the top of said slide, to a second position for tightly holding the stem between said jaw portions in alignment with the recess in the cap being held in said predetermined position, and mechanical means for moving said slide to thereby move the stem into the recess in the cap, said arm moving said clamping jaw portion to a third position wherein said movable clamping jaw portion is spaced from said fixed jaw portion to provide an opening therebetween at the bottom of said slide for releasing the assembled brush therefrom.

35. 9. In a machine for assembling brushes which include an elongated resilient stem, the combination including, an assembly slide having a fixed clamping jaw and a movable clamping jaw supported thereon, said movable clamping jaw having a projecting portion at the bottom thereof for closing the space below said clamping jaws when said jaws are opened to a first position, means including an arm pivotally connected to said slide for moving said movable clamping jaw from the first position for receiving the stem to a second position for tightly holding the stem, said arm moving said movable clamping jaw to a third position wherein said projecting portion is clear of said fixed clamping jaw for releasing the stem, and mechanical means for moving said slide to thereby move the stem held by said jaw.

40. 10. In a machine for assembling brushes which include an elongated stem with bristles secured thereto, the combination comprising, an assembly member for individually receiving the elongated stems of the brushes, feeding means for receiving a plurality of such stems and supplying the same adjacent said assembly member, and ejector means connected to said feeding means including pivotally mounted fingers for receiving one stem and a slide for engaging the one stem and moving the same to rotate the fingers to a position in which the stem drops from the fingers into the assembly member.

65. 11. In a machine for assembling brushes which include a first portion having an elongated resilient stem and bristles secured thereto and a cap which serves as a handle for the brush and which has a recess therein for receiving the stem, the combination comprising, an assembly fixture for receiving a cap and supporting the same in a particular position for securing the first portion of the brush thereto, means for inserting the stem of the first portion in the cap held in said particular position, a container for the caps, con-

veyor means for supplying the caps from the container to said assembly fixture, said container having at least one opening therein of such configuration that the caps can move therethrough in a predetermined position only, said opening communicating with said conveyor means, said conveyor means being shaped so that the caps move therethrough in predetermined position and are supplied to said assembly fixture in said particular position, and means in said container for causing movement of the caps therein so that the caps are urged toward said opening.

12. In a machine for assembling brushes which include a first portion having an elongated resilient stem with bristles secured thereto and a cap which serves as a handle for the brush and which has a recess therein for receiving the stem, the combination including, an assembly fixture for receiving the caps individually and supporting the same in a predetermined position for securing the stem and bristle portion thereto, a container for holding the caps in random positions, conveyor means for supplying the caps from the container to said assembly fixture, said container having openings therein of such configuration that the caps can move therethrough in a predetermined position only, said openings communicating with said conveyor means and means in said container for causing movement of the caps therein so that the caps are urged toward said openings.

13. A machine for assembling brushes which

5
10
15

20
